Primary Examiner — T Chase Nelson*Assistant Examiner* — Rachel Wolfe(74) *Attorney, Agent, or Firm* — Jose Cherson Weissbrot(57) **CLAIM**

The ornamental design for a table lamp, as shown and described.

DESCRIPTION

FIG. 1 is a first perspective view of a table lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the using state of the table lamp thereof; and,

FIG. 10 is an enlarged view of the selected portion in FIG. 1.

The broken lines of alternating length in the drawings are for the purpose of illustrating the boundaries of the enlarged fragment shown in FIGS. 1 and 10.

1 Claim, 10 Drawing Sheets(56)
